UNITED STATES PATENT OFFICE.

GEORGE FELIX DE GRASSE, OF NEW YORK, N. Y.

BLACKBOARD ILLUSION DEVICE.

Specification of Letters Patent.

Patented Oct. 21, 1913.

1,076,649.

Application filed February 13, 1913. Serial No. 748,056.

To all whom it may concern:

Be it known that I, GEORGE FELIX DE GRASSE, a citizen of the United States, residing in the city of New York, borough of Brooklyn, county of Kings, and State of New York, have invented a certain new and useful Blackboard Illusion Device, of which the following is a specification.

This invention is a blackboard illusion device, and the object thereof is to enable an entertainer to draw or sketch an object of some character on the board, and thereafter to illusion the audience into believing that said sketches may be utilized to perform the functions of the objects which they represent.

In one, and the preferred, practical embodiment of the invention, the entertainer, in the presence of the audience, draws a chair and table on the board, *e. g.*, with chalk, whereupon, preferably by the aid of an accomplice, he apparently seats himself upon the chair, with his feet comfortably resting on the table.

The chair and table, sketched as described, are enabled to perform their apparent functions, by means of weight sustaining devices, which, after the sketches are made, are, at the proper moment, surreptitiously projected forwardly from the face of the board, preferably by the assistance of a concealed accomplice, the said weight devices being, of course, properly positioned to support the entertainer in the desired position.

In the accompanying drawings, I have illustrated one practical embodiment of the invention, but the construction shown therein is to be understood as illustrative, only, and not as defining the limits of the invention.

Figure 1 is a view showing the stationary and movable parts of the device of the present invention in perspective. Fig. 2 is a vertical section taken on line 2—2 of Fig. 3. Fig. 3 is a front elevation showing how the device of the present invention appears to the audience.

In said drawings, A indicates a blackboard having suitable means, such as the end pieces a, a, whereby sufficient base is provided to retain the board in upright position. The board is apertured at b, b', b'', to allow for the projection of the several arms or pipes c, c', c'' of the supporting member C therethrough. This supporting mem-

ber C is preferably fixedly mounted on a movable carriage D, in any suitable manner, as by the securing devices d, it being understood that said supporting member is so positioned with respect to the apertures in the blackboard, that, when the carriage is moved into close proximity with said board, the arms, c, c', c'', will register with, and project through, their respective apertures b, b', b''. 60

The following is illustrative of the manner in which the device is employed in entertaining theater-goers. Previous to the raising of the curtain, the blackboard A and the carriage D are so positioned on the stage, that the board will face the audience, and its end pieces or wings a, a, will fully conceal the carriage which is positioned just in rear thereof. A stage hand having secreted himself behind the carriage, the curtain rises, and the entertainer walks out upon the stage, and, picking up a piece of chalk, quickly sketches an object, or objects, on the blackboard, as, *e. g.*, the chair E and the table F, shown. Having finished the sketches, the artist turns, picks up a paper, bows to the audience and, giving a signal to his confederate secreted behind the device, proceeds to seat himself on the chair which he has sketched. The confederate is in readiness for this signal, so that, by the time the entertainer is ready to seat himself, he (the accomplice) has pushed the carriage forward, thereby projecting the arms of the supporting member through the apertures in the blackboard. This having been done, the artist apparently seats himself in the chair with his feet resting on the table, as shown in Fig. 3. In reality, however, he is sitting on the arm or pipe c', resting his back against the pipe c, while the pipe c'' supports his feet. After the lapse of a few minutes, during which the audience is held in suspense, the entertainer, having given a signal to the accomplice, slowly lifts his feet off the table, and rises to a standing posture, whereupon the accomplice withdraws the carriage and the supporting arms, and the deception is complete. 95

It will be manifest that, to obtain the best results, the arms of the member C, which project through the apertures in the board, should closely match, in color, the background which they will have when projecting beyond the surface of the board, for the 100 110

reason that any difference in color would allow the outlines of said arms to be discerned, and the illusion would fail.

Although I have hereinbefore shown and described one embodiment of the present invention, I wish it clearly understood that this form is illustrative, only, and that there are numerous ways in which the spirit of the invention might be carried out; *e. g.*, 5 instead of sketching on a blackboard with chalk, the board might be any color, and paper patterns, cut to represent articles, might be placed on said board. Moreover, the specific construction of the device might 10 be varied to suit the taste of the entertainer; *e. g.*, the carriage might be omitted and the supporting devices manipulated so as to be readily pushed through the apertures in the board. Furthermore, if desired, it is ob- 15 vious that, instead of having an accomplice for projecting the supporting devices, this could be done mechanically. Moreover, the performance of the act need not be limited to one individual, since several individuals, 20 or even one or more animals, may, under certain conditions, participate in it. How- 25 ever performed, it will be obvious that the act is an instructive and pleasing illusion.

Having thus fully described the invention, 30 what I claim as new, and desire to secure by Letters Patent is:—

1. An illusion device embodying a sur- 35 face on which suitable objects may be designated, and means coöperating with said surface whereby said designated objects are made to appear to perform the functions of the real objects which they represent.

2. An illusion device embodying a sur- 40 face on which suitable objects may be designated, and weight sustaining devices coöperating with said surface whereby said designated objects are made to appear to

perform the functions of the real objects which they represent.

3. An illusion device embodying a black- 45 board on which certain objects may be drawn, and a device coöperating therewith for apparently enabling the sketched objects to perform the functions of the real objects which they represent. 50

4. An illusion device embodying a black- 55 board on which certain objects may be drawn, and weight sustaining devices coöperating therewith for apparently enabling the sketched objects to perform the func- 60 tions of the real objects which they repre- 65 sent.

5. An illusion device embodying a black- 65 board on which certain objects may be drawn, and weight sustaining members con- 70 cealed rearwardly of the board and adapted to be surreptitiously projected forwardly of the board so as to sustain the weight of a performer, thereby apparently enabling the performer to use the objects drawn on the 75 board as though employing the real objects represented.

6. An illusion device embodying an aper- 75 tured blackboard on which objects may be designated, a carriage movable toward and 80 away from said blackboard, and weight sup- 85 porting arms fixedly mounted on the car- riage and adapted to coöperate with the apertures in the blackboard, whereby the ob- jects designated on the blackboard are made 90 to appear to perform the functions of the real objects they represent.

In testimony whereof I have signed my name to this specification in the presence of two subscribing witnesses.

GEORGE FELIX DE GRASSE.
